UNITED STATES PATENT OFFICE.

OLIVER NOLAN, OF MINNEAPOLIS, MINNESOTA

BRICK-MACHINE.

No. 811,518.

Specification of Letters Patent.

Patented Jan. 30, 1906.

Application filed July 27, 1905. Serial No. 271,440.

To all whom it may concern:

Be it known that I, OLIVER NOLAN, a citizen of the United States, and a resident of Minneapolis, in the county of Hennepin and State of Minnesota, have invented certain new and useful Improvements in Brick-Machines, of which the following is a specification.

My invention is an improvement in brick-machines; and it consists in certain novel constructions and combinations of parts hereinafter described and claimed.

Referring to the drawings forming a part hereof, Figure 1 is a top plan view of my improved machine. Fig. 2 is an end elevation. Fig. 3 is a detail of one of the partition-plates. Fig. 4 is a bottom plan view, and Fig. 5 is a vertical section on the line 5 5 of Fig. 1. Fig. 6 is a perspective view of my improved machine, showing its position when the brick are removed; and Fig. 7 is a detail of the cam-shaft for starting the brick.

In the practical application of my invention I provide a base A, comprising two pairs of longitudinal stringers a, a', a², and a³, spaced apart and connected at their ends by cross-bars a⁴ a⁵, which extend beyond the forward pair of stringers. A horizontal plate a⁶ rests upon the rear pair of stringers and is provided with a series of spaced grooves a⁷ on its inner edge. A second horizontal plate a⁸ rests upon the outer stringer of the forward pair and upon the extended ends of the cross-bars, and a vertical plate a⁹ is secured to the inner edge of the horizontal plate. A series of grooves a¹⁰ is provided on the inner face of the vertical plate corresponding in position to the grooves on the inner edge of the rear horizontal plate, and a series of braces a¹¹, resting upon the forward horizontal plate, is connected to the vertical plate between the grooves.

A series of partition-plates B rests in the grooves of the rear horizontal plate and the upright plate and upon the upper edge of the inner stringer of the forward pair, and each plate is provided with an opening b in the lower edge thereof. A longitudinal bar b', provided with perforations b² corresponding in position to the partition-plates, is secured to the inner face of the inner stringer of the forward pair. Screw-threaded bolts b³, having hooks b⁴ to engage the openings in the partition-plate, extend downward through

the perforations in the longitudinal bar and 55 are secured thereto by nuts b⁵.

A frame C is connected to the rear horizontal plate by hinges c, and secured to the inner edge thereof is a vertical plate c', provided on its inner face with a series of grooves c² to 60 receive the free ends of the partition-plates. Braces c³ rest upon the hinged horizontal plate and are connected to the vertical plate between the grooves. Upon the lower face of the hinged horizontal plate is secured a series of fingers c⁴ of a length and width corresponding to the distance between the vertical plates and to the distance between the partition-plates, respectively. The above-described fingers are adapted when in their 70 closed position to rest upon the upper edge of the inner stringer of the forward pair and to close the lower part of the opening between the partition-plates, thus forming a series of 75 molds D, closed at the ends by the vertical plates, at the sides by the partition-plates, and at the bottom by the fingers.

Secured to the ends of the frame are handles E for convenience in turning the same upon its hinges.

In practical operation when a series of ten brick are tamped in the molds, it has been found difficult to move them, and the following mechanism is provided for that purpose. A shaft F, provided with a series of cam-fingers f, corresponding in number to the number of molds, is journaled in the ends of the frame, the fingers being adapted when the shaft is rotated to engage the bottom of the mold to aid in starting the brick. For convenience in manipulating the shaft a handle or crank f' is provided. When the shaft is rotated, the fingers engage the movable bottoms, affording a powerful leverage for starting the bricks.

My invention is especially adapted for making concrete brick, but may be used for making brick of clay or other material.

In operation the material is placed in the molds and tamped therein. A board is then 100 laid across the tops of the molds, the ends of the board resting upon the handles E. The swinging frame is then turned backward with the board, and since the position of the brick is reversed the board will be underneath, and when the bottoms are turned back into position the brick will remain upon the board.

In practice my machine is secured to a bench by means of the screws *e*, shown in the back thereof, and the completed brick, with the board or pallet, are turned back upon the bench. The framework is made of cast-iron and the partitions and the bottom fingers of boiler-steel, and the fingers are ordinarily constructed from a single sheet of metal having the openings to receive the partitions milled out.

My machine is simple in construction and easily operated. It is also self-cleaning, the bottoms of the molds performing this function. When it is desired to make colored brick, the coloring-matter may be placed in the bottom of the mold.

Having thus described my invention, what I claim as new, and desire to secure by Letters Patent, is—

- 20 1. In a brick-machine, the combination of a base, comprising pairs of longitudinal stringers spaced apart, cross-bars connecting the ends of the stringers, a horizontal plate resting upon the rear pair of stringers, and provided with a series of spaced grooves on its inner edge, a horizontal plate resting upon the outer stringer of the forward pair, a vertical plate secured to the inner edge of the horizontal plate, and provided with grooves 30 on its inner face corresponding to the grooves on the rear horizontal plate, braces resting on the forward horizontal plate and connected with the vertical plate between the grooves, partition-plates having openings in 35 their lower edges resting in the grooves of the vertical and rear horizontal plates, and upon the inner stringer of the forward pair, a longitudinal bar secured to the inner face of the inner stringer of the front pair and provided with perforations, screw-threaded bolts 40 provided with hooks for engaging the openings in the partition-plates, and extending to the perforations in the longitudinal bar, nuts engaging the bolts, a swinging frame hinged 45 to the rear horizontal plate, and comprising a horizontal plate, a vertical plate secured to the free edge of the horizontal plate and provided with grooves to receive the free edges of the partition-plates, braces resting on the 50 horizontal plate and connected to the vertical plate between the grooves, a plate secured to the lower face of the frame extending across the space between the vertical plates, and provided with openings to receive the 55 partition-plates, and handles secured to either end of the frame at the level of the top of the partition-plates.
2. In a brick-machine, the combination of a base, comprising pairs of longitudinal 60 stringers spaced apart, cross-bars connecting the ends of the stringers, a horizontal plate resting upon the rear pair of stringers and provided with a series of spaced grooves on its inner edge, a horizontal plate resting upon

the outer stringer of the forward pair, a vertical plate secured to the inner edge of the horizontal plate and provided with grooves on its inner face corresponding to the grooves on the rear horizontal plate, braces secured to the outer face of the vertical plate between the grooves, partition-plates resting in the grooves of the vertical plate and the rear horizontal plates and upon the inner stringer of the forward pair, a longitudinal bar secured to the inner face of the inner stringer of the front pair, means for securing the partition-plates to the bar, a frame hinged to the rear horizontal plate, and comprising horizontal and vertical plates, a vertical plate having grooves on its inner face to receive the free edges of the partition-plates, a series of braces between the horizontal and vertical plates, a series of fingers secured to the frame and adapted to close the lower openings between the partition-plates, and handles secured to either end of the frame at a level with the top of the partition-plates.

3. In a brick-machine, the combination of a base, a series of partition-plates spaced apart and secured to the base, a vertical plate having grooves to receive the front edges of the partition-plates and resting upon the base, means for bracing the sections of the horizontal plate between the grooves, a swinging frame hinged to the base and comprising a series of fingers for closing the lower part of the opening between the partition-plates, and a vertical plate provided with grooves to receive the free edges of the partition-plates, means for bracing the sections of the vertical plates between the grooves, and handles secured to the vertical plate at a level with the tops of the partition-plates.

4. In a brick-machine, the combination of a base, a series of partition-plates secured to the base, means for closing the forward opening between the partition-plates, means for bracing said closing means, a swinging frame hinged to the base, and provided with a series of fingers for closing the lower part of the openings between the partition-plates, means on the frame for closing the rear openings between the partition-plates, and handles secured to the swinging frame at a level with the tops of the partition-plates.

5. In a brick-machine, the combination of a base, a series of partition-plates secured to the base, means on the base for closing the forward opening between the partition-plates, a swinging frame hinged to the base, means on the frame for closing the rear openings between the partition-plates, means on the frame for closing the lower opening between the partition-plates, and handles secured to the swinging frame at a level with the tops of the partition-plates.

6. In a brick-machine, the combination of a base, a series of partition-plates secured to

the base, means on the base for closing the forward opening between the partition-plates, a swinging frame hinged to the base, means on the frame for closing the rear openings between the partition-plates, and means on the frame for closing the lower opening between the partition-plates.

7. In a brick-machine, the combination of a base, a swinging frame hinged thereto, and a series of molds, the sides and one end of the molds being secured to the base, and the bottom and the other end of the mold being secured to the swinging frame, and handles secured to the swinging frame at a level with the top of the mold.

8. In a brick-machine, the combination of a base, a swinging frame hinged thereto, a series of molds, the sides and one end of the molds being secured to the base; and the bottom and other end of the molds being secured

to the swinging frame, handles secured to the swinging frame at a level with the top of the mold, and a plurality of cams engaging the bottoms of the molds to assist in starting the same.

9. In a brick-machine, the combination of a base, a swinging frame hinged thereto, a series of molds, the sides and one end of the mold being secured to the base, and the bottom and other ends of the molds being secured to the swinging frame, handles secured to the swinging frame at a level with the top of the mold, a plurality of cams engaging the bottoms of the molds to assist in starting the same, and means for moving the cams in unison.

OLIVER NOLAN.
